SOOT CATCHER FOR FURNACES

Joseph Berinato, Cleveland, Ohio

Application September 25, 1935, Serial No. 42,019

2 Claims. (Cl. 183—77)

This invention relates to soot catchers and has for its object and purpose a means for arresting and collecting the soot from a furnace or the like, as it travels through the smoke pipe or flue toward the chimney.

The means employed consists of a fan which is mounted in the smoke pipe and a soot receptacle comprising a vertical pipe connected to the flue about midway between the furnace and the chimney. At the lower end of this pipe there is a cover which fits telescopically into the vertical pipe and is held in place by a catch fastening. This cover, or receptacle, which extends into the vertical pipe is the soot receptacle.

15 In the drawing:

Fig. 1 is an elevation partly in section of a furnace flue with soot eliminator attached which is also in section.

20 Fig. 2 is an enlarged top view of the fan with retaining ring in section.

Fig. 3 is a fragmentary section of the shaft bearing and fan mounting.

25 Fig. 4 is a sectional view slightly enlarged taken on lines 4—4 of Fig. 1.

25 Referring more particularly to the drawing, an ordinary flue 10 is shown mounted between a furnace 11 and the chimney 12, said flue having attached thereto a soot catcher or eliminating device consisting of a hollow body 13, a fan 14 mounted therein by means of a retaining ring 15 within which the fan is supported rotatably on a shaft 16 and a removable soot trap 17 supported within said hollow body 13.

The fan 14 consists of a plurality of grooved 35 blades 18 attached by rivets or bolts 19 to the flanged ball bearing mounting 20, said fan rotating freely upon shaft 16 mounted through the bearing 21.

The retaining ring 15 is provided with slots 40 22 and 23 in lugs 24 and 25 respectively, small glass inserts 26 and 27 in said slots 22 and 23 being used as bearing surfaces for the ends of shaft 16.

The retaining ring 15 is mounted by means 45 of screws or bolts 28 as near the top of the pipe 13 as possible so that the blades 18 of the fan 14 may project as far up in the flue 10 as possible.

The soot trap 17 has a pair of lugs 29 and 30 at opposed sides of the said trap and a handle 31 attached to the bottom surface thereof, said trap conforming to the shape of the hollow body 13 which may be round, square, octagon or oval. 5 The trap 17 is inserted within the hollow body or pipe 13 through an orifice 32 in the bottom surface of said body, in such way as to have the lugs 29 and 30 on the trap 17 register with the slots 33 and 34 adjacent to said orifice 32, 10 the trap then being rotated so that the lugs 29 and 30 will rest upon the inner flanged surface of the body base.

In operation the suction draft indicated by feathered arrows from the furnace 11, cause the 15 fan 14 to rotate anti-clockwise, drawing the soot from the flue 10 and causing it to drop down within the trap 17 where it may be removed and destroyed.

It will thus be seen that I have provided a very 20 simple, cheap and efficient soot catcher which requires very little time to install, will fit any existing furnace stack and will be free from any trouble, while the inclusion of the fan makes it positive in action. 25

I claim:

1. The combination with a substantially horizontal flue, of a vertical pipe opening at its upper end into said flue, a rotary fan mounted in the upper end of said pipe and having blades which project into said flue, and a receptacle for soot, removably mounted in the lower end of the said pipe, the lower end of said vertical pipe having a notched flange projecting inwardly, and the receptacle having outwardly projecting lugs 30 which may be inserted through said notches and turned to rest upon the flange. 35

2. The combination with a substantially horizontal flue, of a vertical pipe opening at its upper end into said flue, a rotary fan mounted 40 in the upper end of said pipe and having blades which project only partly into said flue during the upper part of their rotation, and a receptacle for soot removably mounted in the lower end of the said pipe, and a ring fastened in the upper 45 end of the vertical pipe and having bearings for the fan shaft.

JOSEPH BERINATO.
